SELECTIVE ORIENTING BUTTON POSITIONING MACHINE

Otto John Huelster, Waterbury, Conn., assignor
to Scovill Manufacturing Company, Waterbury,
Conn., a corporation of Connecticut

Application May 17, 1940, Serial No. 335,715

19 Claims.

(Cl. 218—6)

My present invention relates to a selective orienting mechanism on a button attaching machine. More particularly it relates to a mechanism for selectively orienting buttons or the like having a design on their top and means on the button bearing a definite relation to the design and adapted for engagement with the orienting means on the button attaching mechanism, and constitutes an improvement upon the orienting mechanism disclosed in my co-pending application, Serial No. 272,562, filed May 9, 1939.

In the mechanism of my above-mentioned patent application, the buttons to be oriented are rotated upon their axis at an orienting station whereat a locating device is adapted to engage the engagement means on the button during the rotation thereof to stop the rotation of the button in a definite oriented position, after which, means operate to transfer the button in its oriented position from the orienting station to a button attaching station. The locating means is of a definite form which always orients the button in a definite position with respect to the front of the machine, usually such as to present the button with the design or indicia thereon in upright position when the garment or article to which the button is to be attached is presented to the setting station by being inserted either rearwardly from in front of the machine, or laterally from one side of the machine. Where it is desired to orient the button in any other position with respect to the front of the machine, the locating means must either be replaced by another locating means or the specific elements on the locating means for engaging the engagement means on the button for stopping the rotation thereof has to be adjusted or reset. Of course, such replacement or resetting of the locating means is time-consuming and where resorted to necessitates repeated handling of the garments for the button applying operations where, for example, as in the case of a pair of overalls, one setting is required for the bib buttons, another setting is required for the buttons on the right side of the pants portion, and still another setting is required for the buttons on the left side of the pants portion.

According to my present improvement, the replacing or resetting operations are obviated by providing locating means which are adapted to be selectively operated, as desired. Preferably I provide three separate locating means which may be selectively operated. I have also provided means whereby the separate locating means may be either manually or automatically operated in

any desired sequence or order, depending upon the number and relation of buttons which are to be attached to the garment. An operator is thus enabled to attach both the bib buttons and the buttons on the opposite sides of the pants portion of a pair of overalls with but a single handling of the garment, and this can be accomplished in a simple and expeditious manner, thereby providing for greater efficiency in the button attaching operation.

The invention will be better understood from the detailed description which follows, wherein I have shown several preferred embodiments of my invention, and wherein—

15. Figure 1 is a front elevational sectional view of a button attaching machine embodying my improvements, said figure being taken substantially along the plane of the line 1—1 of Fig. 5.

Fig. 2 is a composite top plan view of the three locating forks by means of which the buttons may be selectively oriented.

Fig. 2a is a side elevation of the middle fork shown in Fig. 2, part thereof being broken away to better illustrate the button engagement means thereof.

25. Figs. 3 and 4 show a fractional top plan and an end elevation, respectively, of a form of selector means different from that shown in Fig. 1.

Fig. 5 is a top plan view of the portions of the machine shown in Fig. 1, with parts thereof broken away.

Fig. 6 is a section taken substantially along the plane of the line 6—6 of Fig. 1.

Fig. 7 is a perspective view of the slide bottom plate forming part of my invention.

Fig. 8 is a perspective view of the spring means adapted to seat on the side bottom plate.

Fig. 9 is a perspective view of a spring slide forming a feature of my invention.

40. Figs. 10, 11, and 12, are sections taken respectively along the planes of the line 10—10, 11—11, and 12—12 of Fig. 5.

Fig. 13 is a fractional front elevation of the treadle control means for the machine.

45. Fig. 14 is a fractional elevation of a modified form of control means.

Figs. 15 and 16 show respectively a top plan and a side elevation partly broken away of one type of button adapted for orienting with the mechanism of my invention.

50. Figs. 17 and 18 show respectively a top plan and a side elevation partly broken away of another type of button or fastener adapted for orienting with the mechanism of the present invention.

Fig. 19 is a composite top plan of three locating forks, partly broken away, by means of which buttons of the type shown in Figs 17 and 18 may be oriented.

Fig. 20 is a side elevation of one of the outer locating forks of Fig. 19.

Fig. 21 is a section taken along the broken line 21—21 of the middle fork of Fig. 19.

Referring to the drawings, the numeral 15 indicates the standard or head of a button attaching machine having attached thereto a main bracket 16 which carries a pair of undercut guides 17 and 18 which, with the main bracket, provide a raceway 19 down which buttons or the like may move by gravity to an orienting station and from there be transferred to a button attaching station 20. The main bracket and the guides carried thereby adjacent their lower ends are curved to lead into the orienting station wherein a button will be supported with its head in a substantially horizontal plane.

Extending across the raceway at an appropriate point therein is any form of cutoff device adapted to deliver one button at a time to the orienting station, said cut-off device being herein shown as an oscillatable disc 21. To oscillate the disc it is provided with a stud 23 to which is connected one end of a link 24, the other end of which is connected to a rock lever 25. For operating the rock lever 25 there is provided a bell-crank lever 26 which is pivoted at 27, one end of said lever bearing upon the free end of the rock lever 25 and the other end carrying an adjustable stud 26a through which movement is imparted to the bell-crank lever by an arm or lever 27a which is operated in synchronism with a pusher slide 28.

The orienting station which is at the bottom of the raceway is defined by rotatable discs 29 and 30 having peripheral grooves therein which are normally spaced apart a distance slightly less than the diameter of the head of a button which is to be oriented so that the peripheries of said discs may contact the periphery of said button head to rotate the button about its axis. Preferably the disc 29 is positively driven and to accomplish this said disc is mounted on a stud 31 which also has mounted thereon a miter-gear 32 which is in mesh with a miter-gear 33 mounted on a stud which carries a pinion 34, which latter is in mesh with a gear sector 35 carried by one end of a lever 36 which gear sector is adapted to be oscillated by an operating cam (not shown).

For orienting a button upon reaching the orienting station, the button must be rotated about its axis and to provide at least three points of engagement not in a straight line for engaging the periphery of the button head, there is provided a third rotatable disc 37 which is carried at the forward end of the pusher slide 28. In this connection it may be stated that the buttons or the like which may be oriented with the present mechanism have engagement means thereon which bear a definite relation to the design on the top of the button. These engagement means may be of various types and, as illustrated in Figs. 15 and 16, the engagement means is in the form of a tab 102b extending inwardly from the shell of the button beneath the head thereof, and in Figs. 17 and 18 the means are in the form of a cut-out or recessed portion 102a in the periphery of the shell.

The present invention contemplates orienting such buttons and fasteners as described above,

in any one of a number, preferably three, predetermined positions at the orienting station. These positions may be described as that wherein the design is in upright position when viewed from the front of the machine, that wherein the design is disposed 90° to the left of the upright position, and that wherein the design is disposed 90° to the right of the upright position.

To selectively orient the buttons in any one of the various predetermined positions, a separate locating means is provided for each position, and means are provided for selectively operating the locating means. As herein disclosed in Figs. 1, 2, 2a, and 5, the locating means which are designed for orienting buttons of the type shown in Figs. 15 and 16 are in the form of three members or locating forks, 38, 39 and 40, which are pivotally mounted in side by side relation within the pusher slide upon a pivot pin 41, and each of said forks is normally biased in a counter-clockwise direction by a coil spring 42 so that the button engaging end thereof is normally disposed out of button engaging relation. It will be noted from an inspection of Figs. 1, 2 and 2a that the locating forks, 38, 39 and 40, at their button engaging ends are of different configuration. The button engaging end of the fork 39 has a recess 39a, extending longitudinally of the fork and adapted to engage the tab 102b on the button shown in Figs. 15 and 16 so as to orient the button with the design or indicia thereon in upright position; the fork 38 has at its button engaging end a recess 38a, the side walls of which extend at right angles to the longitudinal direction of the fork and is adapted to orient a button with the design offset 90° from the upright in a counter-clockwise direction, and the fork 40 at the button engaging end thereof is provided with a recess 40a, the walls of which are disposed at right angles to the longitudinal direction of the fork and is adapted to orient a button with the design disposed 90° from the upright in a clockwise direction. Each of the forks 38, 39 and 40 adjacent their rear ends, is formed with a transverse notch 43, and inwardly of said notch with an upstanding ear 44, the functions for which will presently appear.

Also mounted within the pusher slide 28 and slidable longitudinally thereof, are three selector slides 45, mounted in side by side relation and in alignment with the locator forks 38, 39 and 40. Each of the selector slides has extending upwardly from its top face, approximately midway the length thereof, an ear 46, the function for which will presently appear. On their bottom sides or bases, each of the selector slides 45 is formed with a pair of notches 47 and 48, and extending from the forward end of each of said slides is a spring finger 49 having at the free end thereof a detent 50. The selector slides 45 are supported upon a slide bottom plate 51 which is carried by the pusher slide and has on its upper face a recess 52 within which is mounted in side by side relation three slightly bowed spring clips 53, each having an upwardly directed detent 54 adapted to seat within one of the notches 47 or 48 of each of the selector slides. The slide bottom plate 51 at its innermost end has a transverse notch 55. Normally, the selector slides occupy a position within the pusher slide such that the detent 54 of the spring clips engage in the notches 47; the detent 50 engages within the notch 55; the rearmost ends of the selector slides extend beyond the rear end of the pusher slide; and the ears 46 extend up-

wardly through a slot 56 in the top of the pusher slide.

For selectively controlling the operation of the locating forks through the selective control of the selector slides, a selector control mechanism is mounted rearwardly of the selector slides, or is viewed in Figs. 1 and 5 to the right thereof. This selector control mechanism consists of a shaft 57 upon which is mounted three fingers 58, 59 and 60, disposed in direct alignment with the selector slides, the fingers being diametrically disposed and offset 60° from one another and each one when in its horizontal position is adapted to move the selector slide 45 which is in direct alignment therewith inwardly within the pusher slide 15 as the latter moves rearwardly toward the selector control in the operation of the machine.

The selector shaft 57 is supported in a bracket 61 and is operated through a ratchet device which is mounted on the shaft. This ratchet device consists of a ratchet wheel 63 fixedly mounted on the shaft, said ratchet wheel having a hub which loosely carries the hub of a bracket 62 on which is pivotally mounted a ratchet pawl 64 adapted for engagement with the teeth of the ratchet wheel, said pawl being normally urged into such engagement by a spring-pressed pin 65 carried by the bracket and engaging an ear 66 on the pawl. The bracket 62 also has a stop pin 67 for limiting the throw of the pawl. For indexing the ratchet device there is pivotally connected to the bracket 62 about a pin 68, one end of a link 69, the opposite end of which is connected to a bell-crank lever 70 which is pivotally supported at 71 and through its action upon pawl 64 is adapted to move the ratchet wheel an angular distance of 60° every time the bell-crank lever is tilted about its pivot 71. To limit the movement of the selector shaft 57 by the ratchet device, there is fixedly mounted on the shaft a brake disc 72 having a plurality of radial grooves 73 therein disposed 60° apart which are adapted for cooperation with a spring-pressed detent 73a carried in one arm of the bracket 61. For providing a visual indication of the position to which a button is to be set, the selector shaft 57 has fixedly mounted thereon an indicator 74 having indicia thereon to designate the positions right, left, and front. Where it is desired to manually or arbitrarily set the selector mechanism, there is mounted at the front end of the shaft 57 a knurled thumb wheel 75.

The ratchet pawl 64 is also provided with a handle 64a so that by swinging the pawl in a counter-clockwise direction against the tension of the pawl set pin 65, the ratchet member can be rendered inactive so that the selector shaft will not rotate regardless of the motion of the bell-crank lever.

In Figs. 3 and 4 I have shown an alternative form of finger arrangement on the shaft 57. These fingers 76, 77, 78 are disposed to form a three-leaf clover and the engaging surface of each finger has an angular length sufficient to engage its corresponding selector slide 45 twice in succession as the machine is operated.

It will be apparent that either manual or automatic means may be employed for operating the selector mechanism and these means may be tied in with the press operation, that is, every time the clutch is tripped the selector mechanism will be advanced.

In Fig. 13 I have shown a double pedal arrangement for operating the press and the se-

lector mechanism. By referring to said figure it will be seen that there are two pedals 79 and 80 which are cast integral with hubs 81 and 82, respectively, the hub 81 being fixedly and the hub 82 being rotatably mounted upon a bushing 83 upon a shaft 84 which is supported between the stationary legs 85 of the machine. Also pinned to the bushing 83 is a hub 86 which carries a link 87 which is connected to one end of the bell-crank 70. The hub 82 has a link 88 connected thereto, which controls the tripping of a single revolution clutch (not shown) for controlling the operation of the button attaching machine. The pedal 80 has an arm 89 extending laterally therefrom and projecting under the pedal 79 so that when the pedal 79 is depressed by the foot of an operator, it also depresses the pedal 80, whereas when the pedal 80 is depressed, it does not depress the pedal 79.

In Fig. 14 the pedal control means for the selector mechanism has been omitted and in lieu thereof there is provided a knee operating mechanism. This consists of an angular bracket 90 secured to the lower end of the bell-crank lever 70 and carried by said bracket 90 is a pad 91 which, when laterally struck by the knee of an operator, trips the bell-crank lever 70 to operate the selector mechanism. In this embodiment of the invention there is provided but a single pedal 80a carried by a hub 82a to which is connected a link 88 connected with the clutch control of the machine.

Operation.—In the operations of the mechanism let it be assumed that it is desired continuously to set a series of two buttons in three selected positions, that is, two at the right side, two at the bib, and two at the left side of a pair of overalls so that the design or indicia on the button tops will all be set right side up and that it is desired to accomplish this by the mechanism shown in Figs. 1 and 5, that is to say, with the star shaped selector consisting of the arms 58, 59 and 60. To accomplish this the operator, starting with pedal 80, will have to alternate each pedal operation between the two pedals 79 and 80, for in so doing every time either pedal is depressed a button will be fed and oriented, whereas only when the pedal 79 is depressed will the selector mechanism be reset. Of course if it is desired to set more than two buttons in any one relationship, the operator needs only to continue to depress the foot-pedal 80 until the desired number of buttons are set, after which a depression of foot-pedal 79 brings the next successive selector into operation to change the relationship of the button. Where the machine is equipped with the clover shaped selector rod, as shown in Figs. 3 and 4, the operator only has to continuously press upon the pedal 79, unless he wishes to change the sequence of orienting from a series of two buttons to a larger number, in which case after depressing pedal 79 twice he depresses pedal 80 successively until the desired number of buttons have been set in that position, after which a depression of pedal 79 will result in a button being set in the next successive relationship. In this connection it will be remembered that the length of the cam surfaces on the arms 76, 77 and 78 are such as to engage the same selector slide for two successive 60° movements of the selector shaft.

With the arrangement disclosed in Fig. 14, it will be appreciated that operation of the pedal 80a merely functions to trip the clutch and a supplemental operation of the knee against the

pad 91 is necessary to advance the selector mechanism 58, 59, 60, while two operations of the knee pad 91 are necessary to advance the clover type selector 76, 77, 78. Accordingly, any desired arrangement for the setting of buttons can be accomplished by the proper coordination of the foot and knee in the operation of the machine shown in Fig. 14. Of course, any desired arrangement for the setting of buttons can also be accomplished by proper sequential operation of the pedals 79 and 80 where the star wheel selector is used, as previously explained.

In regard to the coordinated functioning of the machine, it may be stated that at the beginning of the operation the pusher slide is in an intermediate position as viewed in Figs. 1 and 5, with each of the selector slides 45 extending beyond the end of the pusher slide and also that each of the locating forks have their button engaging ends depressed out of button engaging position by the coil springs 42 and each of the detents 50 being in the recess 55 in the bottom plate 51. As a button is released down the raceway to the setting station, let it be assumed that the selector finger 58 is in horizontal position and the locating fork 40 is in alignment therewith. The treadle 80 or 80a is depressed, thus connecting the machine to its source of power through the single revolution clutch and the pusher slide 28 first moves rearward (to the right in Figs. 1 and 5) and this rearward movement of the pusher slide will cause movement inwardly within the pusher slide of that selector 45 which is in line with finger 58 and locating fork 40 upon said selector slide engaging the finger 58, and as said selector slide is moved inwardly the notch 47 therein rides over the detent 54 of the spring clip and the notch 48 engages said detent. Simultaneously with this movement the detent 50 is displaced from the notch 55 and engages the notch 43 in the rear end of the locating fork 40 thereby applying spring tension to said end to move the locating fork in a clockwise direction about its pivot 41 against the force of the biasing spring 42, thereby positioning the button engaging end 40a of the fork to engage the tab of the button which is to be oriented as the button is rotated about its axis at the orienting station. Rotation of the button at the orienting station is effected by the discs 29, 30 and 37, the latter being on the pusher slide and comes into operation when the pusher slide in its movement to the left reaches the orienting station, the rotation being effected through the operation of the gear sector 35, the pinion 34 and the miter-gears 33 and 32. After the button has been oriented, the button is transferred to the setting station 20, the button receiving portion of which is located slightly removed from the orienting station and is adapted to receive a button in the same relationship to the parts of the mechanism that the oriented button occupies at the orienting station except for the change in position of the button due to shifting it from the orienting to the setting station. However, in order to move the button from the orienting station to the setting station without disturbing the spacial relationship set forth, the friction disc 30 is made yieldable. To accomplish this the disc 30, which is an idler, is carried by a bracket 92 which is biased inwardly within a socket by a clip 93 which is urged into bearing engagement with the outer end of the bracket 92 by a spring 94, mounted on a threaded stud 95, which carries an adjusting screw 96. Just prior to the time that the pusher reaches

the setting station, the ear 46 on the selector slide strikes an abutment or shoulder 97 on a bracket 98 mounted on an immovable part of the machine, whereupon the selector slide is displaced from its operative position and moved rearwardly to its normal position within the pusher slide, which action withdraws the detent 50 from the notch 43 in the locating fork and carries it into the notch 55 in the element 51 thereby permitting the fork to swing back to its lower or inactive position under the influence of the spring 42. The button having been positioned in oriented relation at the setting station and the locating fork freed therefrom, the pusher slide is retracted and the setting plunger is depressed to attach the button to the garment. The number of buttons to be successively oriented in each position and the order in which the buttons are to be oriented and attached, will depend upon the form of the selector employed and the treadle control by the operator.

Where a button or fastener, such as shown in Figs. 17 and 18, is to be oriented, the button engaging ends of the locating forks 100, 101 and 102 will be formed with upstanding lugs 100a or 101a for engaging within the recess or cutout portion 102a of the shell on the button or fastener.

From the foregoing detailed description, it will be apparent that I have provided a selective orienting button positioning machine or mechanism whereby, through the use of separate locating means which may be operated either manually or automatically in any desired sequence, an operator is enabled to attach both the bib buttons and the buttons on the opposite sides of the pants portion of a pair of overalls with but a single handling of the garment and this can be accomplished in a simple and expeditious manner. It will also be apparent that the machine is adapted for orienting buttons for positioning upon a garment in any desired relation without resorting to any time-consuming replacing or resetting operations.

It will also be appreciated that although I have shown and described certain preferred embodiments of my invention, that the specific mechanisms disclosed are susceptible of modification and change within the range of engineering skill. Hence, I do not wish to be limited to the details of construction herein disclosed except as limited by the spirit of the invention as defined in the appended claims.

What I claim is:

1. In a button positioning mechanism for buttons or the like having engagement means thereon, in combination, means adapted to periodically receive and support a button for rotation about its axis, means for rotating the button about its axis while in said receiving means, locating means adapted to engage the engagement means on the button during rotation thereof to stop the rotation of the button in any one of a number of predetermined oriented positions, and means for selectively controlling the locating means to determine the orienting of the button.

2. A button positioning mechanism according to claim 1, having means for operating the means for selectively controlling the locating means in a predetermined sequence.

3. In a button positioning mechanism for buttons or the like having engagement means thereon, in combination, means adapted to periodically receive and support a button for rotation

about its axis, means for rotating the button about its axis while in said receiving means, a plurality of locating means each adapted to engage the engagement means on the button during rotation thereof to stop the rotation of the button in a different predetermined oriented position, and means for selectively controlling any one of the locating means.

4. In a button positioning mechanism for buttons or the like having engagement means thereon, in combination, an orienting station adapted to periodically receive and support a button for rotation about its axis, means for rotating the button about its axis at said station, a plurality of locating means, each adapted to engage the engagement means on the button during rotation thereof to stop the rotation of the button in a predetermined oriented position at said station, and means for selectively operating any one of the locating means.

5. A button positioning mechanism according to claim 3, wherein there are three locating means for stopping rotation of the button in any one of three predetermined positions.

6. A button positioning mechanism according to claim 3 having means for operating the means for selectively operating the locating means in a predetermined sequence.

7. A button positioning mechanism according to claim 3, wherein there are three locating means, and wherein the means for selectively controlling the locating means are of a character to sequentially set the three locating means so that each will orient two successive buttons in the same predetermined position.

8. A button positioning mechanism according to claim 3 wherein the means for selectively operating any one of the locating means comprises a plurality of slidable members having parts for interengagement with the locating means.

9. A button positioning mechanism according to claim 3 wherein the means for selectively operating any one of the locating means comprises a plurality of slidable members having parts for interengagement with the locating means, and manually operable means for causing such interengagement.

10. In a button positioning mechanism for buttons or the like having engagement means thereon, in combination, an orienting station adapted to periodically receive and support a button for rotation about its axis, means at said station comprising a plurality of rotatable elements so positioned as to confine and frictionally engage the button and rotate it about its axis, a movable member having a plurality of locating means each adapted to engage the engagement means on the button during rotation thereof to stop rotation of the button in a predetermined oriented position at said station, and a plurality of means

each of which is adapted for selectively operating one of the locating means.

11. A button positioning mechanism according to claim 10, wherein the locating means and the selector means are movable relatively to and with the movable member.

12. A button positioning mechanism according to claim 10, wherein the locating means are pivotally mounted on the movable member, and the selector means are slidable relatively to and with the movable member.

13. A button positioning mechanism according to claim 10, wherein the locating means are pivotally mounted on the movable member, the selector means are slidable relatively to and with the movable member, and wherein the locating means and the selector means have parts adapted for interengagement.

14. A button positioning mechanism according to claim 10, wherein the locating means are pivotally mounted on the movable member and normally biased out of button engaging position, the selector means are slidable relatively to and with the movable member and adapted to engage one of the locating means to bias it into button engaging position.

15. A button positioning mechanism according to claim 10, wherein the locating means and the selector means are movable relatively to and with the movable member, and means for moving the selector means relatively to the movable member.

16. A button positioning mechanism according to claim 10, wherein the locating means and the selector means are movable relatively to and with the movable member, and manually controlled means for moving the selector means relatively to the movable member.

17. A button positioning mechanism according to claim 10, wherein the locating means and the selector means are movable relatively to and with the movable member, and automatically operable means for moving the various selector means relatively to the movable member in a predetermined sequence.

18. A button positioning mechanism according to claim 10, wherein the locating means and the selector means are movable relatively to and with the movable member, and means for moving the selector means relatively to the movable member, said last-mentioned means being automatically sequentially operable by the operation of the machine to which the button positioning mechanism is applied.

19. A button positioning mechanism according to claim 10, having means for disengaging the locating means from a button after it has been oriented.

OTTO J. HUELSTER.
